COASTER STOOL

James Lang, San Antonio, Tex.

Application November 13, 1935, Serial No. 49,631

1 Claim. (Cl. 280—62)

The invention relates to a coaster stool and more especially to a wheeled stool.

The primary object of the invention is the provision of a stool of this character, wherein the same is equipped with wheels so that such stool is handy for use by a person when trimming lawns or edging walks or doing other garden work. The stool is of novel construction so that when occupied by a user it will travel either by pushing or pulling action by such user and thereby allow the user to be seated while working and during progress thereof from a starting to a finishing point. The said pushing or pulling is effected by the feet of the user of the stool.

Another object of the invention is the provision of a stool of this character, wherein the construction thereof assures service so that a user can be seated while executing work, relieving such person from stooping over or standing while at work in trimming lawns or edging side walks or doing other garden or lawn work.

A further object of the invention is the provision of a stool of this character, which is simple in construction, thoroughly reliable and effective in its purpose, light in weight yet strong, durable and inexpensive to manufacture.

With these and other objects in view, the invention consists in the features of construction, combination and arrangement of parts as will be hereinafter more fully described, illustrated in the accompanying drawing, which discloses the preferred embodiment of the invention and pointed out in the claim hereunto appended.

In the accompanying drawing:

Figure 1 is a vertical longitudinal sectional view through a stool constructed in accordance with the invention.

Figure 2 is a sectional view on the line 2—2 of Figure 1 looking in the direction of the arrows.

Figure 3 is a perspective view of the stool showing the same occupied by a user when trimming a lawn.

Similar reference characters indicate corresponding parts throughout the several views in the drawing.

Referring to the drawing in detail, the stool comprises a body frame A, the same being made from strap metal to provide a chassis 5 to which is

fastened the front and rear half loop-like spring seat supports 6 and 7, respectively, carrying a seat 8. The seat is fastened to the upper terminals of said supports by fasteners 9 so that it is in a plane elevated with respect to the chassis 5. Rigidly secured to opposite sides of the chassis 5 close to the front thereof are axle hangers 10 carrying front axles 11 for front wheels 12. Secured medially of the chassis 5 and extended longitudinally beneath the same is a center brace 13, it having 10 a cleat 15 riveted and bolted thereto at 15 and 16, respectively, the outermost bolt 16 of the pair being fitted with a spacer sleeve 17 which is located between the brace 13 and the cleat 14 while the other bolt 16 is fitted between overlapped ends 18 of the frame A, these overlapped ends being suitably riveted together in this relation.

Fitted in the brace 13 and the cleat 14 is a vertical king bolt 19 having swingingly connected thereto a rear wheel fork 20 having journaled 20 therein a rear guide wheel 21 which functions as a caster wheel so that the stool when occupied can be easily guided by the manipulation of the feet of the occupant upon the ground.

In Figure 3 of the drawing the stool is shown 25 occupied and said view will make apparent the mode of use of the stool, particularly by a person trimming a lawn or for edging a side walk or doing other lawn or garden work.

The supports 6 and 7 have riveted or otherwise fastened thereto and located therebetween a cross brace 22.

What is claimed is:

A stool of the character described comprising a body frame formed from a single length of strap 35 metal to provide a substantially square shaped chassis, front and rear half loop-like spring seat supports rising from said chassis, the rear seat supports being riveted to the chassis, a seat fixed to said supports, front and rear axle hangers carried by said chassis, a pivot swingingly connecting the rear axle hangers to said chassis, a cleat fixed in said chassis and receiving said pivot, rivets connecting the rear seat supports to said chassis, wheeled axles journaled in said hangers, and a 45 brace located between the said seat supports and joined therewith intermediate of the same.

JAMES LANG.
